UNITED STATES PATENT OFFICE.

HERBERT E. VAN DORN, OF CHICAGO, ILLINOIS.

DRAWBAR CARRIER.

Application filed September 9, 1921. Serial No. 499,533.

To all whom it may concern:

Be it known that I, HERBERT E. VAN DORN, a citizen of the United States, residing at Chicago, county of Cook, State of Illinois, have invented a certain new and useful Improvement in Drawbar Carriers, and declare the following to be a full, clear, and exact description of the same, such as will enable others skilled in the art to which it pertains to make and use the same, reference being had to the accompanying drawings, which form a part of this specification.

My invention relates to drawbar mechanism for railway cars and the like and has for its object to produce a simple and novel carrier for the front end of the drawbar which will hold the latter yieldingly at a normal elevation, while permitting it to be pressed downwardly when occasion demands and be raised freely.

A further object of the present invention is to produce a simple, novel and compact drawbar carrier which will permit the use of a comparatively long spring for supporting a drawbar so as to permit it to be depressed when necessary.

A further object of the present invention is to produce a simple, novel and compact drawbar carrier which will yieldingly support a drawbar at a normal elevation, but will permit it to be forced downwardly against the tension of the spring and to be freely raised above its normal position.

The various features of novelty whereby my invention is characterized will herein-after be pointed out with particularity in the claims; but, for a full understanding of my invention and of its objects and advantages, reference may be had to the following detailed description taken in connection with the accompanying drawings, wherein:

Figure 1 is a top plan view of a drawbar provided with a carrier arranged in accordance with a preferred form of my invention;

Fig. 2 is a side elevation of the drawbar shown in Fig. 1, together with a part of the underframe of a car to which the drawbar is attached;

Fig. 3 is a view similar to Fig. 1, showing a modification;

Fig. 4 is a view similar to Fig. 2, showing the same modification as that illustrated in Fig. 3;

Fig. 5 is a section taken approximately on line 5—5 of Fig. 2, on an enlarged scale;

Fig. 6 is a perspective view of the bell crank supporting member shown in Figs. 1, 2 and 5;

Fig. 7 is a section, on an enlarged scale, taken approximately on line 7—7 of Fig. 4; and

Fig. 8 is a section on approximately the same scale as Fig. 7, taken on line 8—8 of Fig. 4.

65

Referring to Figs. 1, 2, 5 and 6 of the drawings, 1 represents a drawbar fastened at its rear end by a suitable joint 2 to a part 3 fixed to a car structure; the joint being of any usual and suitable construction 70 to permit the drawbar to swing in a vertical plane and also in a horizontal plane. Underneath the underframe 4 of the car is attached a curved supporting bar 5 serving as a track from which the front end of the drawbar is adapted to be suspended. All of the parts heretofore described may be of any usual or suitable construction since the present invention is not concerned therewith.

Surrounding the drawbar, near the front end of the latter, is a box 6 in which the drawbar slides. The box is illustrated as being made in two halves separated along a horizontal plane and fastened together by means of bolts 7 passing through suitable 85 registering ears 8, but it may be made in any other suitable manner. Slidably supported upon the curved track 5 is a saddle 9. The supporting box is hung from this saddle in such a way that the drawbar is yieldably supported at a normal elevation; may be lifted, preferably freely; and may be pressed downwardly against the tension of the supporting spring when necessary. This is conveniently accomplished by hinging a 95 supporting member at one end to the saddle and at an intermediate point to the box, a spring being placed between the drawbar or box and the other end of the supporting member; the two hinge points being spaced 100 apart from each other in the direction of the length of the drawbar and the spring being so disposed that when the drawbar is pressed downwardly the spring is compressed. In the arrangement shown, the 105 supporting member is in the form of a double bell crank lever. As best shown in Fig. 6, this double bell crank lever consists of two parallel bell crank levers each comprising arms 10 and 11 arranged at right angles to each other, the arms 10 being connected together by a suitable cross-piece 12,

110

integral therewith, and the free ends of the arms 11 being connected together by a detachable cross-piece 13. The two bell crank levers are spaced apart a distance 5 somewhat greater than the width of the box 6 so that they may lie one on each side of the box. The saddle has two downwardly-projecting ears 14 each of which is received in a jaw 15 in the free end of the corresponding bell crank arm 10; bolts 16 passing through the jaws and the ears lying therein completing two co-axial hinge connections between the supporting member and the saddle. At the rear end of the box are two 10 upwardly-projecting ears 17. Each of these ears lies adjacent to the angle of one of the bell crank levers and is pivotally connected or hinged thereto by means of a bolt 18.

On the under side of the box 6 is a spring 20 housing 19 in which is contained a spring 20 acting on a plunger 21 which projects out through the rear of the housing; the spring and plunger extending in the direction of the length of the drawbar.

25 The parts are so proportioned that when they are assembled the arms 10 of the bell crank levers lie approximately horizontally of the drawbar while the arms 11 extend approximately vertically downwardly beside the drawbar; the cross-bar 13 between the lower ends of the arms 11 abutting against the rear end of the plunger. When the parts are in these positions, the spring is under sufficient tension to hold the drawbar up. It 30 will be seen that the horizontal arms of the bell crank levers serve as connecting links between the saddle and the drawbar and, if the spring were removed, these arms would swing downwardly and allow the drawbar to drop. The spring, however, holds the 35 arms normally from swinging in the downward direction, but permits them to swing downwardly through a limited distance whenever a sufficient downward pressure is exerted on the front end of the drawbar. In case a lifting force is applied to the front end of the drawbar, the arms or links 10 simply swing up, the cross-bar 13 moving away from the plunger so that there is no 40 resistance to the lifting of the front end of the drawbar except that exerted by the mere weight of the parts.

45 It will thus be seen that I have produced an exceedingly simple and compact supporting hanger utilizing a comparatively long spring which, by lying snugly against the under side of the drawbar and paralleling the same, does not take up space needed for other purposes.

50 In Figs. 3, 4, 7 and 8 I have shown a somewhat different arrangement, embodying the same principle as heretofore explained. In this arrangement the spring is placed on top of the drawbar and the horizontal arms of the bell crank levers under-

neath the drawbar. This necessitates a supporting saddle or yoke 25 having two long downwardly-projecting arms 26 one of which lies on each side of the drawbar. The supporting box 27 in which the drawbar slides is U-shaped in cross section, being open at the bottom and having a U-shaped cover plate 28 for the open side. The spring housing 29 is located on top of the box and it contains a spring 30 and a plunger 31 similar to the members 20 and 21 in the other form; another difference between the two forms being that the housing is open on the front end and the plunger projects from the front end thereof. The double bell crank member consists of two bell cranks each having arms 32 and 33 arranged at right angles to each other, the free ends of the arms 33 being connected together by a cross-piece 34 integral therewith. The supporting member may therefore be made out of a single piece. In assembling the parts the free ends of the arms 32 are pivotally connected to the downwardly-projecting arms 26 on the saddle by means of bolts 35. A bolt 36 passes through the angles of the two bell crank levers, through ears 37 projecting downwardly from the side walls of the box 27 and through the downwardly-directed flanges on the U-shaped cover plate 28 at the bottom of the box. This bolt therefore serves pivotally to connect the double bell crank lever to the box and to fasten the front end of the bottom cover to the box. A bolt 38, passing through ears 39 projecting downwardly from the rear ends of the side walls of the box and through downwardly-projecting flanges on the cover plate 28, serves to support the rear end of the cover plate.

55 When the parts are assembled, the arms 32 of the bell crank levers lie horizontally beneath the drawbar while the arms 33 extend upwardly beside the drawbar; the cross-piece 34 between the upper ends of the arms 33 being provided with a central lug or projection 40 which engages with the front end of the plunger.

60 When the drawbar is pressed downwardly the tendency is to press the upper ends of the arms 33 of the bell-crank lever and therefore the cross-bar 34 in the rearward direction. This tendency is resisted by the spring-pressed plunger. When a lifting force is applied to the front end of the drawbar, the tendency is to carry the cross-bar 34 away from the spring-pressed plunger and therefore no resistance, except the weight of the parts, is encountered when the front end of the drawbar is lifted.

65 The principle of operation is therefore the same in the two forms of my invention illustrated, the form illustrated in Figs. 1 and 2 being, however, somewhat simpler and lighter than that shown in Figs. 3 and 4.

While I have illustrated and described with particularity only two preferred forms of my invention, I do not desire to be limited to the exact structural details thus 5 illustrated and described; but intend to cover all forms and arrangements which come within the terms employed in the definitions of my invention constituting the appended claims.

10 I claim:

1. In an apparatus of the character described, a drawbar, a member connected with and slidable lengthwise of said drawbar, a support, a lever hinged at one end to said 15 support and at an intermediate point to said member, and a spring between the other end of said lever and said member in position to be stressed when the drawbar is pressed downwardly.

20 2. In an apparatus of the character described, a drawbar, a member connected with and slidable lengthwise of said drawbar, a support, a lever hinged to said member and to said support, the hinge axes 25 being displaced from each other in the horizontal direction, and a spring acting on said 30 lever at such a point that the spring will be stressed when the drawbar is depressed.

3. In an apparatus of the character described, a drawbar, a support, a member connected with and slidable lengthwise of said drawbar, a bell crank lever arranged in rear of said support, one of the arms of 35 the bell crank lever being horizontal and the other vertical, the front end of said lever being hinged to said support, a pivotal connection between the angle of the lever and said member, and a spring between said member and the free end of the vertical arm 40 of said lever.

4. In an apparatus of the character described, a drawbar, a support, a bell crank lever hinged at the angle thereof to the drawbar at a point in rear of said support, 45 a hinged connection between one end of said lever and said support, and a spring acting on the other end of the lever in a direction such that the spring will be stressed when the drawbar is depressed.

50 5. In an apparatus of the character described, a drawbar, a support, a lever hinged to said drawbar and to said support, the hinge axes being displaced from each other in the horizontal direction, and a spring 55 between said lever and said drawbar in position to be compressed when the drawbar is depressed.

6. In an apparatus of the character described, a drawbar, a support, a bell crank 60 lever pivotally connected at its angle to the drawbar, one of the arms of the lever being approximately horizontal and being hinged at its free end to said support, and a spring carried by the drawbar and acting trans-

versely on the other arm in a direction to exert a pressure on the latter arm when the drawbar is depressed.

7. In an apparatus of the character described, a drawbar, a support, two bell crank levers lying on opposite sides of the drawbar and each having one arm approximately horizontal, the free end of each horizontal arm being pivotally connected to said support, pivotal connections between the drawbar and the levers at the angles of the latter, a cross-bar connecting the free ends of the two remaining arms of the levers, and a spring carried by the drawbar and extending longitudinally of the same, said spring acting on said cross-bar in a direction to exert a pressure upon the same when the drawbar is depressed.

8. In an apparatus of the character described, a drawbar, a support arranged above the drawbar, two bell crank levers lying on opposite sides of the drawbar and each having an arm arranged above and approximately parallel with the drawbar and another arm extending downwardly beside the drawbar, a cross-bar connecting the free ends of the downwardly-projecting arms of the levers, a hinge connection between the free end of each of the first mentioned arms and said support; a pivotal connection between each lever, at the angle thereof, with the drawbar; and a spring carried by the drawbar underneath and extending longitudinally of the same, said spring acting on said cross bar in the direction to exert a pressure upon the cross-bar when the drawbar is depressed.

9. In an apparatus of the character described, a support, a drawbar underlying the support, a box surrounding and slidable on said drawbar, a lever hinged to said support 105 and to said box, the hinge axes being displaced from each other in the horizontal direction, and a spring mounted on said box and acting on said lever at a point where it will be stressed when said drawbar 110 is depressed.

10. In an apparatus of the character described, a support, a drawbar underlying the support, a box surrounding and slidable upon the drawbar, a bell crank lever device 115 hinged at the angle thereof to the upper portion of the box, said device having a forwardly-projecting element hinged at the front end to said support and a downwardly-projecting element, and a spring mounted 120 on the under side of said box and acting on said downwardly-extending element in a direction to exert a pressure upon the same when the drawbar is depressed.

In testimony whereof, I sign this specification.

HERBERT E. VAN DORN.
